CIRCUIT INTERRUPTER

**Sigurd I. Lindell, Chicago, and Charles H. Baker,
Maywood, Ill., assignors to S & C Electric Com-
pany, Chicago, Ill., a corporation of Delaware**

Application February 27, 1952, Serial No. 273,638

18 Claims. (Cl. 200—120)

1

This invention relates, generally, to circuit interrupting apparatus and it has particular relation to fuses for use with electric power systems wherein the transient recovery voltage may be substantially greater than the normal frequency recovery voltage. This application is a continuation-in-part of our abandoned application Serial No. 663,832, filed April 22, 1946, and of our abandoned application Serial No. 67,182, filed December 24, 1948.

Certain embodiments of the invention disclosed herein were designed particularly for use in connection with a system operating at 115 kv. and are intended for interrupting, not only relatively low fault currents, but also for interrupting short circuit currents on a power system operating at this voltage, the current interrupter being connected directly in the high voltage circuit and being required to withstand not only the normal frequency recovery voltage but also the transient recovery voltage. It will be understood that the normal frequency recovery voltage is the normal frequency R. M. S. voltage impressed upon the current interrupter after the current has been interrupted and after high frequency transients have subsided. The transient recovery voltage, which may be substantially greater than the normal frequency recovery voltage, is the transient voltage which occurs across the terminals of the current interrupter at the time of arc extinction. Where two or more circuit interrupters of the fuse type are employed in a three phase circuit, the transient recovery voltage is generally considered to be the voltage applied across the first fuse to clear.

When fuses are employed at the higher system voltages on the primary side of large transformer banks and secondary faults occur, they may be required to interrupt low power factor currents of relatively low magnitude under conditions that produce such high normal frequency and transient recovery voltages that conventional fuses flashover between the line terminals. This is particularly true when the primary side of the transformer bank is delta connected or Y-connected with ungrounded neutral. Under such conditions the melting time of the individual fuses of an installation is relatively long and a slight difference in melting characteristics may be sufficient for one fuse to blow ahead of another and attempt to interrupt the low fault current at phase to phase normal frequency system voltage instead of at phase to ground voltage.

When a fuse blows and while the arc is being extinguished, the dielectric strength momentarily

2

established in the interrupting channel at current zero may rise above the rod gap value of the external parallel paths of the same length through still air. A transient recovery voltage may be created and sustained by the arc space sufficient to produce flashover along these parallel paths. In the fuse of the type disclosed in Triplett Patent No. 2,379,200, issued June 26, 1945, which is a solid material type of fuse, and in liquid fuses of the type disclosed in Conrad Patent No. 2,091,431, issued August 31, 1937, the line terminal or ferrule away from which the arc is drawn acts like one rod gap terminal which is paired with the rod-like terminal which moves away therefrom to extend and extinguish the arc. When the voltage between these terminals reaches a value such as to produce a critical gradient in the air adjacent the line terminal or ferrule, streamers are created from the line terminals and breakdown may proceed by propagation through the air to the moving terminal or to the other line terminal or ferrule at the opposite end of the fuse tube at a voltage no higher than the rod gap value of the distance between the first mentioned line terminal and the moving rod-like terminal. Thus even though the interrupting channel of the fuses of the types referred to may possess the ability satisfactorily to interrupt the circuit, in so far as the fault current and recovery voltage are concerned, under certain severe circuit conditions arc over may occur outside of the interrupting channel through the air which will cause flashover of the line terminals. It has been found that this has been caused, in part, by inefficient arrangement of the insulation of the fuse housing and because of insufficient spacing between the line terminals when full consideration is given to not only the normal frequency recovery voltage but also to the transient recovery voltage.

While a solution to the problem thus presented has been worked out in connection with a fuse designed for use with a 115 kv. system, it will be understood that the fuse in which are incorporated the various features of the present invention is not limited to this particular voltage. By suitable and appropriate changes in design, the present invention can be employed in the construction of fuses designed to operate on systems energized at higher or lower voltages. For example, the present invention can be embodied in fuses intended for use on systems operating at 34.5 kv., 46 kv., 69 kv., 92 kv., and 138 kv. Moreover, it will be understood that the present invention may be adapted for use in systems op-

erating at voltages other than these specifically enumerated and can be employed in circuit interrupters of the separable contact type as well as of the fuse type.

The object of the present invention, generally stated, is to provide circuit interrupting apparatus of the high voltage type which shall be simple and efficient in operation and which may be readily and economically manufactured and installed.

Another object is to so proportion the conducting and dielectric components of a high voltage circuit interrupter that the dielectric breakdown value along any path in parallel with the interrupting channel will exceed the dielectric strength of the interrupting channel at any time during or immediately following operation of the fuse so that any restriking of the arc during the interrupting process, or shortly thereafter as a result of reflected voltage surges or prolonged transient recovery voltage, will take place in the bore of the arc passageway and will not take place either through the air outside of the fuse tube between the line terminals or along the inner surface of the fuse tube between it and the filling of solid arc extinguishing material which provides the bore from the surface of which an arc extinguishing medium is evolved to assist in extinguishing the arc.

A further object is to extend within the insulating circuit interrupter housing, such as a fuse tube, the line terminal away from which the rod-like terminal moves on drawing the arc for a substantial distance so as to prevent the formation of a critical gradient in air adjacent the line terminal during the operation of the interrupter and to provide in a structure of this type a dielectric breakdown along any path outside of the interrupting channel substantially equal to the flash-over value of a rod gap of the same spacing as the external line terminals.

Still another object is to increase the resistance of a tubular circuit interrupter housing to bursting pressure along the portion thereof within which the arc is drawn and extinguished.

Another object is to mold the solid arc extinguishing material, such as boric acid, magnesium borate and the like, in the fuse tube under pressure so as to provide intimate contact with the surrounding fuse tube and reduce the likelihood of the arc restriking along the juncture of the solid arc extinguishing material and the surrounding fuse tube.

A still further object of the invention is to provide a devious path along the juncture between the solid arc extinguishing material and the surrounding fuse tube by grooving the latter, as by threading the same, the threads being flattened at the top and bottom so as to avoid sharp changes in direction of the adjoining surfaces.

Still another object of the invention is to reinforce the fuse tube by providing the same with a fibre liner which is arranged to receive the filling of solid arc extinguishing material.

Another important object of this invention is to so proportion the conducting and dielectric components of a high voltage switch of the separable contact type that the dielectric breakdown value along any path in parallel with the interrupting channel will exceed the dielectric strength of the interrupting channel at any time during or immediately following operation of the switch and separation of its contacts so that any restriking of the arc during the interrupting process, or shortly thereafter, as a result of reflected voltage

surges or prolonged transient recovery voltage, will take place in the bore of the arc passageway and will not take place either through the air outside of the interrupter housing between the external line terminals or along the inner surface of the housing between it and the lining of arc extinguishing material which provides the bore from the surface of which an arc extinguishing medium is evolved to assist in extinguishing the arc.

Another important object of this invention is to extend within the insulating housing the line terminal away from which the movable contact moves on drawing of the arc for a substantial distance so as to prevent the formation of a critical gradient in air adjacent this line terminal during the operation of the switch and drawing of the arc and to provide in a structure of this type a dielectric breakdown value along any path outside of the interrupting channel substantially equal to the flashover value of a rod gap of the same spacing as the external line terminals and substantially greater than the breakdown value between the fixed and movable arcing terminals or contacts at any time during or after arc current interruption.

Still another object of this invention is to construct the insulating housing which is coextensive with the arc passageway therein and extensions from the line terminals as to be free from voids so that the dielectric around the passageway and extensions is composed of insulating material other than air.

Other objects of the invention will, in part, be obvious and in part appear hereinafter.

The invention is disclosed in the embodiments thereof shown in the accompanying drawings and it comprises the features of construction, combination of elements and arrangement of parts which will be exemplified in the constructions set forth hereinafter and the scope of the application of which will be indicated in the appended claims.

For a more complete understanding of the nature and scope of this invention, reference may be had to the following detailed description taken in connection with the accompanying drawings, in which:

Figure 1 is a view, in side elevation, of a fuse construction in which the present invention is incorporated;

Figures 2A-2B-2C, taken together, show a longitudinal sectional view through the fuse construction of Figure 1, the fuse being shown in the unblown condition;

Figures 3A-3B are views similar to Figures 2A-2B, but showing the fuse in the blown condition;

Figure 4 is a detail sectional view, at an enlarged scale, showing how the solid arc extinguishing material is molded into grooves or threads on the inner surface of the fuse tube;

Figure 5 is a detail sectional view illustrating a modified form of the invention in which the fuse tube is provided with a reenforcing fibre liner;

Figure 6 is a longitudinal sectional view of a circuit interrupting device of the separable contact or switch type constructed in accordance with this invention, the switch being shown in the closed position; and

Figure 7 is a view, similar to Figure 6, but showing the switch in the open circuit position.

Referring now particularly to Figure 1 of the drawings, it will be observed that the reference character 10 designates an insulating tube which

forms the housing for the circuit interrupter of the fuse type to be described in detail herein-after. At its opposite ends the insulating tube 10 is provided with external or line terminals 11 and 12 which are arranged to have contact engagement with suitable terminal clips as is more fully set forth in Lindell Patent No. 2,484,839, issued October 18, 1949. However, it will be understood that any suitable form of terminal clip can be employed in practicing the present invention and that the particular form of terminal clip disclosed in the patent of Lindell, just referred to, is mentioned solely for illustrative purposes. The terminals 11 and 12 are formed of suitable conducting material such as brass.

As disclosed more fully in the copending application of Sigurd I. Lindell, Serial No. 663,832, filed April 22, 1946, the fuse construction herein disclosed is arranged to be mounted so that, when the fuse blows, it will automatically move under the influence of gravity and the biasing force of the contact clips to a position where a relatively large air gap is provided between the upper line terminal 11 and the associated terminal clip which is connected to the circuit. In order to provide such operation the fuse has a latch tube 13 which is secured at its lower end to a latch release flange 14 that, together with the tube 13, is arranged to be moved upwardly in a manner to be described hereinafter for the purpose of unlatching the locking mechanism and permitting the fuse to fall or drop out to the open circuit position.

The fuse is arranged to exhaust downwardly on operation thereof through the lower line terminal 12. In order to cool and condense the arc products and limit the escape of flame from the lower end of the fuse, a condenser assembly may be provided on the lower line terminal 12. Its shell is indicated at 16. The internal details of construction of the condenser will be set forth more fully hereinafter.

Particular reference will now be made to Figure 2B. As there shown, the fuse tube 10 is formed of insulating material. This may be a phenolic condensation product, such as "Bakelite" or it may be a melamine tube. The tube 10 may be a solid rolled phenolic condensation product tube and may have a baked coating of melamine enamel on the outside and the inside to provide weather and arc resisting surfaces superior in these respects to the surface of the tube itself.

At the central portion of the tube 10 its internal diameter is reduced as indicated at 18 for the purpose of providing a section which has increased resistance to bursting pressure, it being understood that relatively high pressures may be generated within the tube 10 in the portion thereof where the arc is drawn and extinguished. This configuration also aids in more uniformly distributing the dielectric flux in the air about the ends of the terminals embedded therein. The thickness of the tube wall should be such as to withstand without puncture one half of the normal frequency voltage.

With a view to providing an arcing passageway from whose surface an arc extinguishing medium can be evolved, cakes 19 of solid arc extinguishing material are positioned along the bore of the reduced diameter section 18. These cakes 19 are annular in form and when placed one above the other provide a continuous bore 20 in which the arc may be drawn and extinguished. Various solid arc extinguishing materials may be em-

ployed. For example, boric acid or magnesium borate may be used.

As indicated hereinbefore, difficulty has been encountered in failure of the fuse by improper operation as a result of arcing over along the juxtaposed surfaces of the tube 10 and of the solid arc extinguishing material 19. It is believed that this has been caused by imperfections in the bond between the two materials which had been attempted by the use of a dielectric cement. This difficulty has been overcome in accordance with the present invention.

As shown more clearly in Figure 4 of the drawings, the inner surface of the thickened portion 18 of the wall of the tube 10 is grooved by threading the same as indicated at 21. However, care is taken not to provide sharp points and valleys on and between the threads 21 by flattening the inner edges thereof as indicated at 22 and also providing flat surfaces 23 between the adjacent threads 21. This construction provides a devious, roundabout or indirect path along the juxtaposed surfaces of the two materials which is substantially greater (at least forty per cent greater) than the total length of the stack of cakes 19 of solid arc extinguishing material.

Another important feature of the present invention is the manner in which the cakes 19 of solid arc extinguishing material are placed in the fuse tube 10. Initially their outer diameter is such as to permit their being readily placed within the threaded bore of the enlarged section 18 of the tube 10 around an arbor. Thereafter the cakes are successively subjected to a molding pressure of approximately 4000 pounds per square inch by a hollow ram as a result of which the solid material is firmly compacted in place in and between the threads 21. Thereafter the arbor is withdrawn, leaving the bore 20 which forms the arc passageway.

The melamine coating over the threads 21 provides an arc resisting surface which reduces the likelihood of flash-over therealong as might be the case if such a protection covering over the surface of the phenolic condensation product were not used.

At each end of the column of cakes 19 of solid arc extinguishing material there is provided a reinforcing ring of suitable insulating material such as fibre. One of these is indicated at 27 at the upper end in Figure 2B and the other is indicated at 28 at the lower end. The reinforcing ring 28 is flared outwardly to facilitate the outward flow of the products of the arc, as will be readily understood.

Movably mounted within the bore 20 in the cakes 19 of solid arc extinguishing material and substantially filling the same is a rod-like terminal 29. At its upper end the terminal 29 is provided with a contact tip 30 which is arranged to be engaged by contact fingers 31 the upper ends of which are turned inwardly and biased inwardly by a garter spring 32. The contact fingers 31 extend upwardly from a contact fitting 33 which, in part, serves to hold the reinforcing ring 27 in place.

An electrical connection between the line terminal 11 and the contact fingers 31 is provided by a conducting tube or terminal extension 34 of brass, copper, copper alloy or other suitable conducting metal. It will be noted that the lower end of the conducting tube 34 is threaded onto the contact fitting 33 and that a nut 35 is threaded onto the upper end thereof and also is threaded into the line terminal 11 thereby form-

ing an extension thereof. This is shown in Figure 2A. A lock nut 36 serves to hold the contact nut 35 in place.

As will hereinafter appear, when the fuse blows, it is desired that the rod-like terminal 29 be moved rapidly through the bore 20 in order to extend the arc therein and permit the heat thereof to evolve an arc extinguishing medium, such as water vapor, from the bore 20 so as to deionize the arc space and assist in extinguishing the arc. For this purpose a helical compression spring 37 is located within the conductor tube 34 and bears against the fitting 33 and the under side of a spring seat 38 which is secured to the lower end of a compression tube 39 which may be formed of brass. The compression tube 39 carries a base 40 at its upper end from which a stud 42 depends. On opposite sides of the lower end of the stud 42 links 43 (only one of which is shown) are pivoted by a pin 44. Between the links 43 a pulley 45 is rotatably mounted on a pin or shaft 46.

A cable connector assembly, shown generally at 49, extends over the pulley 45 and provides both mechanical and electrical connection to the rod-like terminal 29 for effecting retraction thereof and also for maintaining electrical circuit connection thereto while it is moving through the bore 20 and after the contact tip 29 has moved away from the contact fingers 31. The cable connector assembly 49 comprises a core 50 formed of a large number of strands of relatively fine wire, such as copper wire and an outer sheath 51 formed by a closely wound coil spring preferably of stainless steel. One end of the cable connector assembly 49 is connected to the contact tip 30 of the rod-like terminal 29, as shown in Figure 2B, while the other end is connected to a strap or cable link 52. The lower end of the strap or link 52 is secured, as by rivets 53 to the contact fitting 33.

When the fuse blows, as will be described hereinafter, the spring 37 is released and it moves the compression tube 39 upwardly, carrying with it the pulley 45. Because of the mechanical arrangement thus provided, the rod-like terminal 29 moves at twice the speed that the compression tube 39 is moved and its extent of movement is twice as great. The compression tube 39 carries with it the base 40 which moves upwardly until it engages a cap 54 which is secured to the upper end of the latch tube 13. As set forth hereinbefore, the upward movement of the latch tube 13 lifts therewith the flange 14, as shown in Figure 3A, to effect unlatching of the fuse so as to permit it to drop out. The latch tube 13 moves upwardly until a shoulder 55, Figure 2B, on the spring seat 38 engages a shoulder 56, Figure 2A, on the inside of a stop tube 57 which is secured to a fitting 58 that forms part of the fuse mounting contact mechanism which is described in more detail in Lindell Patent No. 2,484,339, issued October 18, 1949. The stop tube 57 is held in place in the fitting 58, in part, by a sleeve 59 over which the lower end of the tube 57 is rolled and which bears against the under side of the fitting 58. The latch tube 13 is held in the position shown in Figure 2A of the drawings by a coil compression spring 62 which is located between the tubes 13 and 57 and at its lower end bears against the upper end of a tubular extension 63 from the flange 14 and at its upper end against the underside of a collar 64 which is secured to the upper end of the stop tube 57.

The fitting 58 has integrally formed ears 65

and 66 on opposite sides between which links are pivoted to provide for contact engagement between the line terminal 11 and the cooperating fuse clip. The details of construction are more fully set forth in the Lindell patent last referred to. As shown in Figure 2A the upper line terminal 11 is secured to the upper end of the tube 10 by suitable screws 67, two of which are there illustrated.

As indicated hereinbefore, difficulty has been encountered in fuses of the prior art in flashover of the fuse tube from or to the line terminal away from which the movable terminal is withdrawn. It is believed that this has been caused by the overstressing of the air immediately adjacent the end of the line terminal nearer to the movable terminal after it has been moved to extend the arc away from the line terminal, on operation of the fuse.

With a view to relieving this condition and providing a more efficient design, the line terminal 12 is extended by an exhaust tube 70 of suitable conducting material, such as brass while, of course, retaining the conducting tube 34. As illustrated in Figures 2B-2C, the exhaust tube or terminal extension 70 is positioned inside of the tube 10 at its lower end and extends upwardly. The inturned upper end bears against the fibre retaining ring 28 and serves to hold the same in place. At its lower end the tube 70 is connected to the lower line terminal 12 by a nut 71 which, as shown in Figure 2C, is threaded to the lower end of the tube 70 and also is threaded into the line terminal 12. A lock nut 72 serves to hold the nut 71 in place.

Near its upper end the exhaust tube 70 carries a narrow bridge or fuse element support 73 from which a rod-like terminal 74 extends upwardly. A tubular adapter 75 and nuts 76 cooperate to hold the terminal 74 in place on the bridge 73 and to provide good electrical and mechanical connection therewith. The terminal 74 is connected to the rod-like terminal 29 by a coiled fusible element 77, preferably of silver, and a strain element 78, preferably a high strength alloy wire, such as "Nichrome" or "Chromel" wire. It will be understood that the bridge 73 is securely fastened to the exhaust tube 70 so that it makes proper mechanical and electrical connection therewith.

As shown in Figure 2C, the lower line terminal 12 may be secured to the lower end of the tube 10 by suitable screws 81, two of which are shown.

It will be apparent that the conducting tube 34 and the tapered fitting 33 perform at their end of the tube 10 the same function as does the exhaust tube 70 with its tapered end at its end of the tube 10 in more uniformly distributing the dielectric stress during and after circuit interruption.

In order to mount the condenser shell 16 a reducer fitting 82 is threaded into the lower end of the lower line terminal 12 and the shell 16 is threaded thereon, as illustrated in Figure 2C. Within the condenser shell 16 is a condenser 83 of the type shown in Triplet Patent No. 2,379,200, issued June 26, 1945, which serves to cool or condense the products of the arc resulting from the blowing of the fusible and strain elements 77 and 78 as will be readily understood.

It is desirable that the condenser shell 16 be closed to the atmosphere except when the fuse blows. This prevents the introduction of extraneous matter into the interior of the fuse. For this purpose a valve seat 84 is threaded into the lower end of the condenser shell 16 and a valve

cover 85 is arranged to cooperate therewith. The valve cover 85 is slidably mounted on the valve seat 84 by a stud 86 and is held in the closed position by a coil compression spring 87 which reacts between the upper surface of the valve seat 84 and a nut 88 at the upper end of the stud 86. When sufficient pressure is generated within the condenser shell 16 on the blowing of the fuse, the arc products expand through apertures 89 in the valve seat 84, lift the valve seat 84 and are exhausted into the atmosphere.

Instead of forming the tube 10 with the central portion 13 of reduced diameter, as shown in Figure 2B, a liner may be provided for accomplishing the same purpose of reenforcing the tube at this point. As shown in Figure 5, a tube 10', similar to the tube 10, but having a uniform bore throughout, may be used together with a liner 91 of horn fibre or similar material, such as "Bakelized" horn fibre. Preferably, the liner 91 is first formed and then the tube 10' of "Bakelite" or melamine is formed therearound under heat and pressure. An insulating resin, such as melamine, serves to bond the liner 91 in place in the tube 10' when the latter is formed of material such as "Bakelite." The inner bore of the liner 91 may then be grooved, as described hereinbefore and illustrated in Figure 4, for receiving the cakes 19 of solid arc extinguishing material which may be molded or compacted therein to provide the required structure. The fibre liner acts not only to absorb the shock of the high pressure created by high current arcs but also in conjunction with the arc extinguishing material 19 serves to extinguish any incipient arc appearing along the adjoining surfaces thereof.

With a view to indicating the order of the dimensions employed in constructing the fuse shown in the drawings and described hereinbefore, reference will now be made to the general dimensions of the various parts thereof.

As indicated hereinbefore, the fuse disclosed herein is designed particularly for use with a system operating at 115 kv. However, the principles of construction can be used for voltages other than this and the specific dimensions to be referred to hereinafter are to be considered only for illustrative purposes.

The fuse tube 10 or 10' may be about fifty-two inches long and have an outside diameter of about three inches. The internal diameter of the tube 10 or 10' at the ends is about 1 1/8 inches while the internal diameter of the bore for receiving the cakes 19 of solid arc extinguishing material may be 1 7/8 inches. The threads 22 may be formed by a one inch pipe thread tap which is ground to provide the desired contour of the threads, as described. The rod-like terminal 29 is about twenty-seven inches long and is arranged to have a travel of about twenty-two inches from the position shown in Figure 2B to the position shown in Figure 3B. When the rod-like terminal 29 is in the retracted position, shown in Figure 3B, it extends into the tube 10 about fifteen inches from the upper end thereof. The exhaust tube 76 extends into the lower end of the tube 10 for about fifteen inches with the result a gap of about twenty-two inches in length is provided within the bore 20, substantially midway between the ends of the line terminals 11 and 12 each of which is coextensive with its end of the fuse tube for about two inches. This relationship is illustrated by the broken lines in Figure 1.

It will be apparent from the foregoing data

75

that the length of the interrupting channel in the bore 20 is approximately equal to the sum of the lengths of the extensions from the line terminals 11 and 12, i. e., twenty-two inches for the interrupting channel and twenty-eight inches for the sum of the lengths of the extensions from the line terminals 11 and 12 measured from their nearer ends. The minimum wall thickness of the tube 10 at the inner ends of the embedded extensions 34 and 70 of the terminals 11 and 12 is such that its dielectric strength is equal to at least half of the flashover value from one terminal 11 to the other terminal 12 or, as indicated hereinbefore, is capable of withstanding without puncture one-half of the normal frequency voltage so as to prevent puncture of the tube walls and completion of breakdown from one terminal extension to the other in air if a critical gradient is approached in the air outside 20 of the bore 20.

The wall thickness and diameter of the tube 10 are important also in controlling the dielectric stress in the air outside of the tube adjacent the ends of the rod-like terminal 29 and the tube 70 when the former is in the blown position as illustrated in Figure 3B. These dimensions are chosen and the ends are shaped so as to allow the stress lines emerging from the terminal extensions 34 and 70 to diverge appreciably before entering the air. Thereby the voltage gradient in the surrounding air is lowered. It would be impractical to employ such a thickness of solid insulation for the tube 10 as would materially reduce the total voltage imposed on the air. The terminal extensions 34 and 70, which may be considered as embedded terminals, are shielded by the solid dielectric material making up the tube 10. With respect to the outside air around the tube 10 these embedded terminals fall into a class between rod gaps and sphere gaps. These embedded terminals 34 and 70 also tend to shield the corners of the line terminals 11 and 12 and to reduce the stress along the co-extensive surface of the tube 10. The net result 40 of the complete structure with the proportions indicated is that the breakdown strength along any gap involving the air outside of the tube 10 and between any two of the terminals is raised to a level considerably above the rod gap value 50 for the same distance.

The potential existing between the terminal extension 34 and the rod-like terminal 29 at the upper end of the tube 10 and the terminal extension 70 at the lower end is applied not only to the ends of the bore 20 in the arc extinguishing material 19 but also to the ends of the devous path over the juxtaposed threaded exterior surface of the arc extinguishing material 19 and interior surface of the tube 10, Figure 4, or interior surface of the fibre liner 91, Figure 5. Since this devous path between the conducting parts at its ends is substantially greater in length than the path through the bore 20, any voltage breakdown that takes place always will occur in the latter and not in the former. If such a devous path were not provided and the arc extinguishing material 19 were assembled having a path over its exterior surface about equal in length to the length of the bore 20, this is the likelihood that arcing will take place over this exterior surface rather than through the bore 20 when the conducting parts at the ends of these parallel paths are subjected to high potentials that may arise for various reasons. If such arcing over the exterior surface should occur, the

11

circuit may not be properly cleared and the interrupter may fail thereby requiring other means in the circuit to interrupt the current flow.

While the present invention has been described particularly in conjunction with a fuse of the solid arc extinguishing material type, it will be apparent that it is applicable to other types of circuit interrupters, such as those which include separable contacts between which an arc is drawn. Also, it may be used in a fuse of the liquid type such as disclosed in Conrad Patent No. 2,091,431, issued August 31, 1937.

Referring now particularly to Figures 6 and 7 of the drawings, it will be observed that the reference character 110 designates, generally, a switch or circuit interrupter of the general type shown in Lindell et al. Patent No. 2,351,826, issued June 24, 1944, and constructed in accordance with this invention. The switch or circuit interrupter may be employed separately or it may be employed in conjunction with the disconnecting switch blade or switch construction shown in this patent or in application Serial No. 41,597, filed July 30, 1948. Since the present invention is directed particularly to the features of construction of the switch 110, the operating mechanism therefor will not be described in detail herein other than to point out a certain portion of the same for illustrative purposes.

The switch or circuit interrupter 110 includes a pair of line terminals 111 and 112. It will be recognized that the line terminal 111 may be connected to the stationary contact of the disconnecting switch shown in the aforesaid Lindell et al. patent while the line terminal 112 is arranged to have sliding or wiping contact engagement with a flexible contact member carried by the switch blade. The line terminal 112 also serves as a housing for a portion of the operating mechanism which will be referred to in more detail hereinafter. However, it will be understood that the line terminals 111 and 112 may constitute conventional line terminals of a switch when the switch or circuit interrupter 110 is employed by itself. A portion of the operating mechanism that can be employed in conjunction with the switch 110 is illustrated, generally, at 113 within the housing 112.

The line terminals 111 and 112 are held in insulated spaced relation by an insulating housing that is indicated, generally, at 114. As shown, the construction is such that the line terminals 111 and 112 do not overlap the outer surface of the insulating housing 114.

It will be observed that the insulating housing is tubular in form and that it may be formed by a tube 115 of insulating material. The insulating material for the tube 115 preferably is weather-proof, and for this purpose a phenolic condensation product, or melamine may be employed. Also, with proper rearrangement of the parts, the tube 115 may be formed of porcelain.

The tube 115 has a central bore 116 the length of which is equal to about one half the length of the tube 115 and it is placed midway between its ends. Within the bore 116 there is a stack of fibre washers 117 which together provide a bore 118 that forms an arc passageway between the line terminals 111 and 112 in which the arc incident to the operation of the switch 110 is drawn and extinguished. The fibre washers 117 preferably have a press fit with the bore 116 and a suitable cement is provided for holding them in place. While the stack of fibre washers 117 is illustrated as being employed to provide the arc passageway 118 from whose surface an arc ex-

12

tinguishing medium is evolved when it is subjected to the heat of the arc, it will be understood that other materials, such as boric acid and magnesium borate can be employed. If the tube 115 is formed of insulating material, such as melamine, which inherently has arc extinguishing properties, then the stack of fibre washers 117 can be omitted and the arc passageway or bore 118 provided in the tube 115 itself.

The end portions of the tubular insulating housing 115, when it is formed of a resin, such as those referred to above, have threaded bores 121 and 122 the diameter of which is greater than the diameter of the bore 116. The inner surfaces 123 and 124 of each of the threaded bores 121 and 122 is tapered toward the ends of the bores 116. The purpose of this configuration will be apparent presently.

Each of the line terminals 111 and 112 is provided with a tubular extension 125 and 126, respectively, of conducting material. The extensions 125 and 126 project into the housing 115 for substantial distances. Preferably the sum of their lengths is about equal to the length of the bore 118 and the extensions 125 and 126 are of equal length. The inner ends 127 and 128 of these extensions 125 and 126 are tapered to conform to the tapered surfaces 123 and 124 at the inner ends of the threaded bores 121 and 122. The purpose of this tapered configuration is to aid in distributing substantially uniformly the electrostatic stress in the housing and in the outside air which is incident to the drawing of an arc within the bore 118 and its extinguishment. This distribution of electrostatic stress is aided by having the insulating housing 114, which is coextensive with the bore 118 and the tubular extensions 125 and 126 of sufficient wall thickness and free from voids so that the dielectric therearound is composed solely of insulating material other than air. There is then no likelihood of the insulation being severely stressed as may be the case under certain operating conditions if there were voids left in the insulating housing 114, the voids being filled by air.

It will be observed that the tubular extensions 125 and 126 are externally threaded so that they can be screwed into the threaded bores 121 and 122. In addition the line terminal 111 is threaded onto the extension 125. The extension 126 may be formed integrally with the line terminal 112 as shown. Suitable gaskets 129 and 130 are provided at the ends of the insulating housing 114 to provide a weathertight construction.

Within the bore 118 and tubular extension 126 there is positioned a movable rod-like contact member 133 the upper end 134 of which is hollow and split to provide flexibility and contact surfaces 135 are provided thereon for contact engagement with a cylindrical contact surface 136 at the lower end of the tubular extension 125. The diameter of the contact surface 136 is the same as the diameter of the bore 118 and, in effect, constitutes a continuation thereof. The tubular extension 125 has a large diameter bore 137 therein for the purpose of facilitating the escape of the products of the arc which are the result of its heat and which are principally in the form of metal vapor and gas, the latter resulting from the evolution of arc extinguishing material from the stack of fibre washers 117 and a trailer or follower to be described.

The rod-like contact member 133 is hollow at its upper end, as indicated, and a rod 138 is telescoped therein. The rod 138 is rockably mounted

near its lower end by a pin 139 which extends through the contact member 133. The rod 133 is provided for connection to a trailer or follower 140 of insulating material. The trailer or follower 140 is formed of material which evolves an arc extinguishing medium when it is subjected to the heat of the arc. For example, it may be formed of methyl methacrylate resin. If desired, the trailer or follower 140 may be formed of other similar insulating material such as fibre, melamine, etc. It will be understood that the trailer or follower 140 is drawn into the bore 118 along with the rod-like contact member 133. When the switch or circuit interrupter 10 is operated under load, an arc is drawn between the contact surfaces 135 at the upper end of the rod-like contact member 133 and the contact surface 136 at the lower end of the tubular extension 125. Since the trailer or follower 140 of insulating material is drawn into the bore 118, as shown in Figure 7, the arc thus formed is confined between the outer surface of the trailer or follower 140 and the inner surface of the stack of fibre washers 117 or the bore 118. The arc thus confined is quickly extinguished.

It will be observed that there is a path between the tubular extensions 125 and 126 along the juxtaposed surfaces of the tube 115 and the stack of fibre washers 117 which is parallel to and co-extensive with the path therebetween through the arc passageway 118. Under certain operating conditions these paths are subjected to high potential stress because of the voltage that is applied to the extensions 125 and 126. Further, the trailer 140 as shown in Figure 7 augments this high potential stress since it substantially fills the arc passageway 118 and thus reduces the space which the arc can occupy. It is for these reasons that it is desirable that the dielectric around the arc passageway 118 and the extensions 125 and 126 be free from voids and for this purpose the stack of fibre washers 117 has a press fit with the bore 116 in the tube 115 and is cemented into place. This construction insures that any arc formed between the line terminals 111 and 112 will be drawn in the bore 118 and not along the parallel path between the tube 115 and stack of fibre washers 117.

It will be understood that any suitable means can be employed for moving the rod-like contact member 133 into and out of engagement with the tubular extension 125. For example, the operating mechanism 113, referred to above can be employed. This mechanism includes a lever 143 which is pivoted at 144 to the lower end of the movable rod-like contact member 133. At its other end the lever 143 is pivoted at 145 to a link 146 which, as shown, is pivoted at 147 to a web 148 that may be formed integrally with the lower line terminal 112. The link 146 has an integrally formed foot portion 149 which serves as a stop to limit the movement of the contact member 133 in the closing or opening directions. Intermediate the ends of the lever 143 at 150 an arm 151 is pivoted for operating the linkage to move the contact member 133 into and out of engagement with the extension 125. The arm 151 is fastened to a shaft 152 which extends transversely of the line terminal 112 and has detents at its ends, one of which is illustrated at 153. It will be understood that the detents 153 are arranged to be operated by suitable means, such as by cams on the disconnecting switch blade for rocking the shaft 152 to shift the arm from the position shown in Figure 6 to the position shown in Figure 75 to

7. A coil tension spring 154 is strained between the pivot point 145 and the shaft 152 to provide an overcenter toggle linkage and to hold the contact member 133 in the closed position shown in Figure 6 or in the open position shown in Figure 7. Since further changes can be made in the foregoing constructions and different embodiments of the invention can be made without departing from the spirit and scope thereof, it is intended 10 that all matter shown in the accompanying drawings and described hereinbefore shall be interpreted as illustrative and not in a limiting sense.

What is claimed as new is:

1. In a high voltage circuit interrupter for use with electric power systems wherein the transient recovery voltage may be substantially greater than the normal frequency recovery voltage, in combination, an insulating tube having an arcing passageway substantially equal in length to half the tube length and located substantially midway its ends, the inner surface of said tube coextensive with said arcing passageway being threaded, a filling of arc extinguishing material having its external surface threaded and interlocked with said inner surface of said tube whereby a devous path is provided therebetween and having a bore forming said arcing passageway, external terminals at the ends of said tube for connection to the circuit and between which said recovery voltages are applied, a stationary metallic extension from each of said terminals inside said tube extending to the adjacent end of said arcing passageway and for distances substantially beyond any part of the associated external terminal, and means for drawing an arc in said passageway on operation of the interrupter, said metallic extensions acting to distribute electrostatic stress at locations substantially one fourth the length of said tube from each end after interruption of current flow therethrough and applying voltage stress to the ends of said devous path which because of its greater length as compared to the length of said arcing passageway and the arc extinguishing material threaded into said tube has a higher voltage break down strength than does said arcing passageway and insuring that any restriking of an arc between said terminals will occur in said arcing passageway and not along a path between the former and external to the latter.
2. In a high voltage fuse for use with electric power systems wherein the transient recovery voltage may be substantially greater than the normal frequency recovery voltage, in combination, an insulating tube with the internal central portion for substantially half its length of reduced diameter to provide increased wall thickness for strengthening the tube at this section and having its inner surface threaded, a filling of arc extinguishing material having its external surface threaded and interlocked with said inner surface of said reduced diameter section and having a bore from the surface of which an arc extinguishing medium is evolved due to the heat of an arc, said threaded inner surface of said reduced diameter portion and said arc extinguishing material interlocked therewith providing a devous path therebetween having a substantially greater creepage distance over the juxtaposed surfaces than is provided over the surface of said bore, line terminals at the ends of said tube for connection to the circuit and between which said recovery voltages are applied, a rod-like terminal movable through said bore, con-

ducting means interconnecting said rod-like terminal and one of said line terminals, spring means biasing said rod-like terminal toward said one line terminal, the arcing end of said rod-like terminal in the retracted position remaining in said bore near one end thereof, stationary conducting means extending from the other line terminal toward said bore for a distance several times the length that said other terminal is coextensive with said tube, and fusible means interconnecting said rod-like terminal and the last mentioned conducting means and holding the former against the retractile force of said spring means until the same blows on the occurrence of a predetermined overload in the circuit in which the fuse is connected, said rod-like terminal after release and said conducting means applying voltage stress to the ends of said devious path which because of its greater length as compared to the length of said bore and the arc extinguishing material threaded into said tube has a higher voltage break down strength than said bore.

3. In a high voltage fuse for use with electric power systems wherein the transient recovery voltage may be substantially greater than the normal frequency recovery voltage, in combination, an insulating tube with the internal central portion for substantially half its length of reduced diameter to provide increased wall thickness for strengthening the tube at this section, the inner surface of said reduced diameter section being grooved, a filling of arc extinguishing material compacted into said grooves whereby the voltage breakdown strength along the devious path thus provided between said tube and said arc extinguishing material substantially equals that over the exterior surface of the fuse tube between its ends, said filling of arc extinguishing material having a central bore from the surface of which an arc extinguishing medium is evolved due to the heat of an arc, line terminals at the ends of said tube for connection to the circuit and between which said recovery voltages are applied, a rod-like terminal movable through said bore, conducting means interconnecting said rod-like terminal and one of said line terminals, spring means biasing said rod-like terminal toward said one line terminal, the arcing end of said rod-like terminal in the retracted position remaining in said bore near one end thereof, conducting means extending from the other line terminal toward said bore for a distance several times the length that said other terminal is coextensive with said tube, and fusible means interconnecting said rod-like terminal and the last mentioned conducting means and holding the former against the retractile force of said spring means until the same blows on the occurrence of a predetermined overload in the circuit in which the fuse is connected.

4. In a high voltage fuse for use with electric power systems wherein the transient recovery voltage may be substantially greater than the normal frequency recovery voltage, in combination, an insulating tube with the internal central portion for substantially half its length of reduced diameter to provide increased wall thickness for strengthening the tube at this section, the inner surface of said reduced diameter section being threaded with the inner edges of the threads and the portions of the tube therebetween flattened, a filling of arc extinguishing material compacted into said threads whereby the voltage breakdown strength along the devious path thus provided between said tube and said arc extinguishing material substan-

tially equals that over the exterior surface of the fuse tube between its ends, said filling of arc extinguishing material having a central bore from the surface of which an arc extinguishing medium is evolved due to the heat of an arc, line terminals at the ends of said tube for connection to the circuit and between which said recovery voltages are applied, a rod-like terminal movable through said bore, conducting means interconnecting said rod-like terminal and one of said line terminals, spring means biasing said rod-like terminal toward said one line terminal, the arcing end of said rod-like terminal in the retracted position remaining in said bore near one end thereof, conducting means extending from the other line terminal toward said bore for a distance several times the length that said other terminal is coextensive with said tube, and fusible means interconnecting said rod-like terminal and the last mentioned conducting means and holding the former against the retractile force of said spring means until the same blows on the occurrence of a predetermined overload in the circuit in which the fuse is connected.

5. In a high voltage fuse for use with electric power systems wherein the transient recovery voltage may be substantially greater than the normal frequency recovery voltage, in combination, an insulating tube formed of a phenolic condensation product, a fibre liner along the central portion of said tube for substantially half its length to provide increased resistance to internal pressure at this section and having its inner surface threaded, a filling of arc extinguishing material having its external surface threaded and interlocked with said inner surface of said fibre liner and having a bore from the surface of which an arc extinguishing medium is evolved due to the heat of an arc, said threaded inner surface of said liner and said arc extinguishing material interlocked therewith providing a devious path therebetween having a substantially greater creepage distance over the juxtaposed surfaces thereof than is provided over the surface of said bore, line terminals at the ends of said tube for connection to the circuit and between which said recovery voltages are applied, a rod-like terminal movable through said bore, conducting means interconnecting said rod-like terminal and one of said line terminals, spring means biasing said rod-like terminal toward said one line terminal, the arcing end of said rod-like terminal in the retracted position remaining in said bore near one end thereof, stationary conducting means extending from the other line terminal toward said bore for a distance several times the length that said other terminal is coextensive with said tube, and fusible means interconnecting said rod-like terminal and the last mentioned conducting means and holding the former against the retractile force of said spring means until the same blows on the occurrence of a predetermined overload in the circuit in which the fuse is connected, said rod-like terminal after release and said conducting means applying voltage stress to the ends of said devious path which because of its greater length as compared to the length of said bore and said arc extinguishing material threaded into said fibre liner has a higher voltage break down strength than said bore.

6. In a high voltage fuse for use with electric power systems wherein the transient recovery voltage may be substantially greater than the normal frequency recovery voltage, in combina-

17

tion, an insulating tube formed of phenolic condensation product, a fibre liner along the central portion of said tube for substantially half its length to provide increased resistance to internal pressure at this section, the inner surface of said fibre liner being grooved, a filling of arc extinguishing material compacted into said grooves whereby the voltage breakdown strength along the devious path thus provided between said liner and said arc extinguishing material substantially equals that over the exterior surface of the fuse tube between its ends, said filling of arc extinguishing material having a central bore from the surface of which an arc extinguishing medium is evolved due to the heat of an arc, line terminals at the ends of said tube for connection to the circuit and between which said recovery voltages are applied, a rod-like terminal movable through said bore, conducting means interconnecting said rod-like terminal and one of said line terminals, spring means biasing said rod-like terminal toward said one line terminal, the arcing end of said rod-like terminal in the retracted position remaining in said bore near one end thereof, conducting means extending from the other line terminal toward said bore for a distance several times the length that said other terminal is coextensive with said tube, and fusible means interconnecting said rod-like terminal and the last mentioned conducting means and holding the former against the retractile force of said spring means until the same blows on the occurrence of a predetermined overload in the circuit in which the fuse is connected.

7. In a high voltage circuit interrupter for use with electric power systems wherein the transient recovery voltage may be substantially greater than the normal frequency recovery voltage, in combination, an insulating tube having a centrally located arc passageway the diameter of which is substantially less than the internal diameter of the end portions of the tube and a length that is equal to about the sum of the lengths of said end portions, the inner surfaces of said end portions tapering toward the ends of said arc passageway, a terminal at each end of said tube having a tubular extension of conducting material lining the adjacent end portion thereof and having a tapered end portion conforming to the associated tapered section of the tube end portion to distribute substantially uniformly the electrostatic stress incident to circuit interruption, and means for drawing and extending an arc in said passageway.

8. The invention, as set forth in claim 7, wherein the minimum wall thickness of the insulating tube at the tapered section is such that the dielectric strength thereof is equal to at least one half of the flashover value between the terminals over said fuse tube.

9. In a high voltage circuit interrupter for use with electric power systems wherein the transient recovery voltage may be substantially greater than the normal frequency recovery voltage, in combination, an insulating tube having the internal central portion for a length substantially equal to half the tube length of reduced diameter to provide increased wall thickness for strengthening the tube at this portion, the inner surface of said reduced diameter portion being threaded, a filling of arc extinguishing material compacted into the threads and having a central bore from the surface of which an arc extinguishing medium is evolved due to the

18

heat of the arc, said bore being located substantially midway the ends of said tube, the end portions of said tube being substantially equal in length and the inner end surfaces thereof tapering toward the ends of said arc passageway, external terminals coextensive with the ends of said tube for connection to the circuit and between which said recovery voltages are applied, a stationary metallic tubular extension from each of said terminals lining the adjacent end portion of said tube for a distance substantially beyond any part of the associated external terminal and having a tapered inner end portion conforming to the associated tapered inner end surface of the tube end portion to distribute substantially uniformly at each end of said arcing passageway the electrostatic stress incident to circuit interruption, and means within said tube for drawing an arc in said passageway on operation of the interrupter, said metallic extensions acting to distribute electrostatic stress at locations substantially one fourth the length of said tube from each end after interruption of current flow therethrough and insuring that any restriking of an arc between said external terminals will occur in said arcing passageway and not along a path between the former and external to the latter.

10. In a high voltage circuit interrupter for use with electric power systems wherein the transient recovery voltage may be substantially greater than the normal frequency recovery voltage, in combination, an insulating tube having external line terminals at its ends for connection to the circuit and between which said recovery voltages are applied, stationary conducting means within said tube extending from each line terminal toward the other for a distance several times the diameter of said tube, the inner surface of said tube between said stationary conducting means being grooved, a filling of granular arc extinguishing material compacted into said grooves and having a central bore from the surface of which an arc extinguishing medium is evolved due to the heat of an arc, and means for drawing an arc in said bore on operation of the interrupter, the length of said bore being sufficient to provide for drawing and extinguishing therein an arc likely to be formed on operation of the interrupter, said conducting means acting to distribute voltage stress applied to said line terminals to prevent arcing therebetween externally of said tube, and said arc extinguishing material compacted in said grooves insuring that the arc between said conducting means will be drawn in said bore.

11. In a high voltage circuit interrupter for use with electric power systems wherein the transient recovery voltage may be substantially greater than the normal frequency recovery voltage, in combination, an insulating tube having line terminals at its ends for connection to the circuit and between which said recovery voltages are applied, stationary conducting means within said tube extending from each line terminal toward the other for a substantial distance, the inner surface of said tube between said stationary conducting means being threaded, a filling of arc extinguishing material having a central bore from the surface of which an arc extinguishing medium is evolved due to the heat of an arc and having its external surface threaded and interlocked with said threaded inner surface to provide a devious path therebetween having a substantially greater creepage distance over the juxtaposed surfaces than is provided over the surface of said bore, and means for drawing an arc in said bore

on operation of the interrupter, the length of said bore being sufficient to provide for drawing and extinguishing therein an arc likely to be formed on operation of the interrupter, said conducting means acting to distribute voltage stress applied to said line terminals to prevent acting therebetween externally of said tube and applying the voltage stress to the ends of said devious path, and said arc extinguishing material in said threads insuring that the arc between said conducting means will be drawn and extinguished in said bore.

12. In a high voltage circuit interrupter for use with electric power systems wherein the transient recovery voltage may be substantially greater than the normal frequency recovery voltage, in combination, an insulating tube having line terminals at its ends for connection to the circuit and between which said recovery voltages are applied, stationary conducting means within said tube extending from each line terminal toward the other for a substantial distance, a high strength tubular insulating liner between said conducting means in said insulating tube to provide increased resistance to internal pressure, the inner surface of said liner being threaded, a filling of arc extinguishing material having its surface threaded and interlocked with said inner surface and having a central bore from the surface of which an arc extinguishing medium is evolved due to the heat of an arc, said threaded inner surface of said liner and said arc extinguishing material interlocked therewith providing a devious path therebetween having a substantially greater creepage distance over the juxtaposed surfaces than is provided over the surface of said bore, and means for drawing an arc in said bore on operation of the interrupter, the length of said bore being sufficient to provide for drawing and extinguishing therein an arc likely to be formed on operation of the interrupter, said conducting means acting to distribute voltage stress applied to said line terminals to prevent arcing therebetween externally of said tube and applying the voltage stress to the ends of said devious path, and said arc extinguishing material in said threads because the greater length of said devious path as compared to the length of said bore insuring that the arc between said conducting means will be drawn and extinguished in said bore.

13. In a high voltage circuit interrupter for use with electric power systems wherein the transient recovery voltage may be substantially greater than the normal frequency recovery voltage, in combination, an insulating tube having a centrally located arc passageway the diameter of which is substantially less than the internal diameter of the end portions of the tube and the length of which is equal to about the sum of the lengths of said end portions, the inner surfaces of said end portions tapering toward the ends of said arc passageway, a terminal at each end of said tube having a tubular extension of conducting material lining the adjacent end portion thereof and having a tapered end portion conforming to the associated tapered section of the tube end portion to distribute substantially uniformly the electrostatic stress incident to circuit interruption, the ends of said extensions adjacent the respective ends of said passageway being spaced substantially beyond any other portion of the respective terminal in the direction toward the other terminal whereby the production of a critical voltage gradient in air adjacent said ter-

minals incident to the drawing and extinguishing of the arc and flashover of the external surface of said insulating tube are prevented, and a contact member movable to and from engagement with one of said tubular extensions through said arc passageway and the other extension.

14. In a high voltage circuit interrupter for use with electric power systems wherein the transient recovery voltage may be substantially greater than the normal frequency recovery voltage, in combination, an insulating tube having a centrally located arc passageway the diameter of which is substantially less than the internal diameter of the end portions of the tube and the length of which is equal to about the sum of the lengths of said end portions, the inner surfaces of said end portions tapering toward the ends of said arc passageway, a terminal at each end of said tube having a tubular extension of conducting material lining the adjacent end portion thereof and having a tapered end portion conforming to the associated tapered section of the tube end portion to distribute substantially uniformly the electrostatic stress incident to circuit interruption, the ends of said extensions adjacent the respective ends of said passageway being spaced substantially beyond any other portion of the respective terminal in the direction toward the other terminal whereby the projection of a critical voltage gradient in air adjacent said terminals incident to the drawing and extinguishing of the arc and flashover of the external surface of said insulating tube are prevented, a contact member movable to and from engagement with one of said tubular extensions through said arc passageway and the other extension, and a trailer of insulating material movable with said contact member through said one extension into said passageway whereby any arc between said one extension and said contact member is drawn in the space between said trailer and said passageway.

15. In a high voltage circuit interrupter for use with electric power systems wherein the transient recovery voltage may be substantially greater than the normal frequency recovery voltage, in combination, a tubular insulating housing, a lining of arc extinguishing material intimately engaging the inner surface of said housing and providing an arc passageway with the space between it and the outer surface of said housing free from voids whereby no path is provided between said housing and liner along which an arc is likely to strike, a terminal at one end of said housing and a contact member movable through the other end of said housing and said passageway for connection to the circuit and between which said recovery voltages are applied, and an extension from said terminal inside said housing extending to the adjacent end of and in tandem with said passageway for engagement and disengagement by said contact member, the end of said extension adjacent said passageway being spaced substantially beyond any other portion of said terminal in the direction of movement of said contact member to open position whereby the production of a critical voltage gradient in the air adjacent said terminal incident to the drawing and extinguishing of the arc and flashover of the external surface of said housing are prevented.

16. The invention, as set forth in the preceding claim, wherein the lining is formed by a stack of fibre washers having a press fit with the inner surface of the housing.

17. In a high voltage circuit interrupter for use

with electric power systems wherein the transient recovery voltage may be substantially greater than the normal frequency recovery voltage, in combination, a tubular insulating housing, a lining of arc extinguishing material intimately engaging the inner surface of said housing and providing an arc passageway with the space between it and the outer surface of said housing free from voids whereby no path is provided between said housing and liner along which an arc is likely to strike, a terminal at one end of said housing and a contact member movable through the other end of said housing and said passageway for connection to the circuit and between which said recovery voltages are applied, an extension from said terminal inside said housing extending to the adjacent end of and in tandem with said passageway for engagement and disengagement by said contact member, the end of said extension adjacent said passageway being spaced substantially beyond any other portion of said terminal in the direction of movement of said contact member to open position whereby the production of a critical voltage gradient in the air adjacent said terminal incident to the drawing and extinguishing of the arc and flashover of the external surface of said housing are prevented, and a trailer of insulating material movable with said contact member into said passageway whereby any arc between said extension and said contact member is drawn in the space between said trailer and the inner surface of said liner.

18. In a high voltage circuit interrupter for use with electric power systems wherein the transient recovery voltage may be substantially greater than the normal frequency recovery volt-

age, in combination, a tubular insulating housing, a lining of arc extinguishing material interfitting closely with the inner surface of said housing and providing an arc passageway, cement intimately bonding said lining to said inner surface of said housing whereby the space between said arc passageway and the outer surface of said housing is free from voids and no path is provided between said housing and liner along which an arc is likely to strike, a terminal at one end of said housing and a contact member movable through the other end of said housing and said passageway for connection to the circuit and between which said recovery voltages are applied, and an extension from said terminal inside said housing extending to the adjacent end of and in tandem with said passageway for engagement and disengagement by said contact member, the end of said extension adjacent said passageway being spaced substantially beyond any other portion of said terminal in the direction of movement of said contact member to open position whereby the production of a critical voltage gradient in the air adjacent said terminal incident to the drawing and extinguishing of the arc and flashover of the external surface of said housing are prevented.
